UNITED STATES PATENT OFFICE.

CHESTER M. ANGELL, OF CHICAGO, ILLINOIS, ASSIGNEE TO VESTA BATTERY CORPORATION, OF CHICAGO, ILLINOIS, A CORPORATION OF ILLINOIS.

BATTERY-PLATE FILLING MACHINE.

Application filed March 15, 1923, Serial No. 625,847. Renewed March 22, 1926.

This invention relates to a machine which is to be used in the preparation of plates used in storage batteries. Such plates are usually made by casting a grid of lead or other suitable metal and then filling the spaces in the grid with a suitable material.

One of the principal objects of this invention is the provision of improved means for filling the grids with paste.

Another object of the invention is the provision of improved means for moving and handling the grids during the filling operation.

Other and further important objects of this invention will be apparent from the disclosures in the drawings and the accompanying specification.

The invention (in a preferred form) is illustrated in the drawings and hereinafter more fully described.

On the drawings:

Figure 1 is a diagrammatic plan view of a battery plate grid filling plant.

Figure 2 is a plan view of the first unit of such plant.

Figure 3 is a section on the line 3—3 of Figure 2.

Figure 4 is a side elevation of the front portion of the first unit.

Figure 5 is a section on the line 5—5 of Figure 4.

Figure 6 is a section on the line 6—6 of Figure 5.

As shown on the drawings:

The grid filling plant comprises three units 10, 11 and 12. In the first unit 10, one side of the grid is filled; in the next 11, the other side is filled; and, in the third 12, the side of the grid first filled is finished.

The present case relates more particularly to improvements in the first unit.

The first unit 10 comprises a platform 13 supported by uprights 14. Above the platform 13 is another platform 15. On the latter platform is a paste box 16 and in front of the paste box is arranged the mechanism for feeding grids through the paste box.

This mechanism consists of a strip of paper 23 which is passed along the machine beneath the paste box. This paper strip is supported by an endless belt 25 which at one end passes around a drum 19. While this moving strip of paper 23 exerts considerable propelling effort upon the grids, this is not sufficient to force the grids through the paste

box. This requisite additional force is obtained by providing pins 21 on the periphery of the drum 19 for engagement with the lugs 18 of the lowermost of a stack of grids. The height of the pins 21 and the diameter of the drum 19 is such that before a pin has dropped below and therefore out of engagement with the lug of the grid moved thereby, it has moved the latter a greater distance than the depth of the grid so that the next grid can drop down behind it on the platform 15. The pins also engage the under side of the next grid so that the stack is lifted and the movement of the bottom grid is facilitated. The grids are stacked up on the platform 15 with their lugs in engagement with angle bars 17. Only the outer arm of each of the bars 17, however, extends downwards as far as the platform 15 so that a space is left beneath the other arm for the passage of the lugs 18 of the lowermost grid, as shown in Figure 6.

To these angle bars 17 are attached other angle bars 31, and to these in turn are connected crossed braces 32. The latter are secured to members 33 which are notched for detachable engagement with the front wall 34 of the paste box. From each member 33 depends a bar 35 to the lower end of which are attached a pair of guides 27 adapted to engage the upper surface of the grids adjacent their edges. Bars 35 are releasably clamped to the wall 34 of the paste box by catches 38 (Fig. 5).

The bars 35 are connected near their upper ends by a brace 36 which supports by member 37 the rear end of a guide 38 adapted to engage the central portions of the grids.

The forward end of the guide 38 is supported by a brace 30 extending between a pair of brackets 29 attached to the edge of the platform 15.

The lugs of the grids are guided by means of members 26 adjustably carried by the brackets 29 by means of screws 20.

The paste box 16 has journaled therein a shaft 39 having a rectangular cross-section over that part thereof which is within the box. To each side of the squared portion of the shaft is attached a blade or trowel 40 which is adapted both to press the paste into the grid and also to remove the greater part of the excess paste.

The front end of the paste box is supported by the lateral portions of the front wall 110

34 which rest on the platform 15, the central portion being spaced away from the platform to allow of the passage of the grids therebeneath.

5 The rear end of the paste box is supported by brackets 41 (Figure 3) which rest loosely upon brackets 42 attached to uprights 43 carried by the frame of the machine.

The rear wall 44 of the paste box acts as 10 a scraper to remove excess paste and for that purpose is made adjustable. For this purpose there are attached to the end wall 44 lugs 45 which project over a cross bar 46 carried by the side walls of the paste box by

15 means of brackets 47. In threaded engagement with these lugs are screws 48, the lower ends of which bear against the cross bar 46.

The scraper wall 44 is locked in adjusted position by a thumb screw 49 mounted on a 20 cross-bar 50.

The operation is as follows:

A stack of grids is placed with their lugs 25 in engagement with the angles 17 and the machine is started. The rotation of the drum 19 and parts connected thereto causes the paper strip 23 and the endless belt to move under the stack of grids. At the same time one pair of pins 21 engages the lugs on the lowermost grid and moves it forward. 30 Then the next pair of pins pushes the next grid after the first so that a continuous line of grids is pushed through the machine.

In this movement the grids are guided by the guides 26, 27 and 38 so that the line can- 35 not buckle.

The grids then pass under the front wall

34 of the paste box and are operated upon by the rotating blades or trowels 40.

Finally the grids pass under the scraper 44 which removes the excess of the paste. 40

I am aware that numerous details of construction may be varied through a wide range without departing from the principles of this invention, and I therefore do not purpose limiting the patent granted otherwise 45 than necessitated by the prior art.

I claim as my invention:

1. In a machine for handling battery plate grids, a platform, stacking means for the grids, a paste box above said platform, 50 means for pushing a line of grids along said platform from said stacking means under said paste box by pressure upon the first grid in the line whereby the grids are all maintained in contact with each other, and an endless web of material fed with said grids along said platform and upon which the latter rest.

2. In a machine for handling battery plate grids, a platform, stacking means for the 60 grids and a paste box above said platform, slots in said platform adjacent each side thereof, a drum below said platform, studs upon the periphery of the drum adapted to extend through the slots and engage the 65 lowermost grid and move it along the platform towards the paste box, and an endless web of material fed with said grids along said platform upon which the latter rest.

In testimony whereof I have hereunto sub- 70 scribed my name.

CHESTER M. ANGELL.
